UNITED STATES PATENT OFFICE.

FREDERICK R. BISHOP, OF NORTH ATTLEBORO, MASSACHUSETTS.

DESIGN FOR AN OPTICAL MOUNTING.

Application filed February 21, 1927. Serial No. 20,843. Term of patent 14 years.

To all whom it may concern:

Be it known that I, FREDERICK R. BISHOP, a citizen of the United States, residing at North Attleboro, in the county of Bristol and State of Massachusetts, have invented a new, original, and ornamental Design for an Optical Mounting, of which the following is a specification.

In the accompanying drawings which

form a part of this specification Figure 1 is a front view and Figure 2, a transverse vertical central section of an optical mounting embodying my new design.

I claim:

The ornamental design for an optical mounting, as shown.

FREDERICK R. BISHOP.
